Carl Krauss, % Lakewood Engineering and Mfg. Co.,
212 N. Carpenter St., Chicago, Ill.

Filed July 20, 1959, Ser. No. 56,839

Term of patent 14 years

(Cl. D83—1)

FIG. 1 is a front perspective view of a massage unit and couch combination embodying my new design;

FIG. 2 is a bottom plan view of the massage center thereof;

FIG. 3 is a top plan view of FIG. 1; and

FIG. 4 is a rear elevational view of the massage center.

The dominant features of my design reside in the full line portions of the drawings.

I claim:

The ornamental design for a massage unit and couch combination, substantially as shown and described.
